UNITED STATES PATENT OFFICE.

HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

SEAM FOR WOVEN-WIRE BELTS.

Application filed December 18, 1922. Serial No. 607,557.

To all whom it may concern:

Be it known that I, HAMILTON LINDSAY, a citizen of the United States, residing at Cleveland, in the county of Cuyahoga and State of Ohio, have invented a certain new and useful Improvement in a Seam for Woven-Wire Belts, of which the following is a full, clear, and exact description, reference being had to the accompanying drawings.

This invention relates to a method of joining the ends of a wire fabric to form an endless belt which is particularly useful in Fourdrinier paper machines. More particularly, my invention is concerned with a seam for lacing the ends of a belt having a special weave as set forth in my co-pending application, Serial No. 525,403, filed Dec. 28, 1921.

20 Briefly, the belt illustrated in my co-pending application embodies a fabric wherein the lower knuckles of the longitudinally extending or warp wires pass continuously beneath two or more cross or lay wires instead of only one. Accordingly, the warp wires are divided into groups, each preferably of three wires in number, during the weaving operation, and are manipulated so that one group forms one plane of the 25 shed while the other two groups form the other plane of the shed, while the shuttle passes therebetween and across the loom. These groups are interchanged after each 30 stroke of the shuttle whereby the fabric so formed has short knuckles on the upper side of the belt and long knuckles on the lower side thereof. This results in a construction which gives a longer wearing surface to the under side of the belt, thus increasing the life thereof.

One of the difficulties encountered in joining the ends of the belt above described is the provision of a seam which does not fill the interstices (which would render it 45 difficult for water to pass through this seam when the belt is in use) and at the same time forms a sufficient support between the ends of the fabric so as not to strain the pulp. Another difficulty is the arrangement of closing wires which do not displace the lay wires so as to distort the mesh.

Accordingly, one of the objects of my invention is the provision of a seam having a

sufficient space for the passage of water therethrough, and sufficient support between the ends of the fabric so that the pulp is properly drained and at the same time supported adjacent the seam, whereby the paper is not weakened. Another object is the provision of a seam for use in a belt 55 constructed in the manner above set forth which will not weaken the wires adjacent the ends of the fabric. Furthermore, my invention includes a seam, the wires of which lie in substantially the same plane as the 60 warp wires so that the wear occasioned by the passage of the seam across a suction box is not greater than that occurring on other parts of the belt.

The preferred embodiment for carrying 70 out my invention is illustrated in connection with the accompanying drawings, and is hereinafter described in detail. The essential features are summarized in the 75 claims.

In the drawings, Figures 1 and 2 are plan views illustrating the ends of a belt having a weave constructed as heretofore described and illustrating the application of a stitching wire, wherein Fig. 1 shows the top side of the belt, while Fig. 2 shows the bottom side thereof; Figs. 3 and 4 are views similar to Figs. 1 and 2 and show the application of a second stitching wire; Figs. 5 and 6 are views corresponding to Figs. 3 80 and 4 with the application of a closing wire; while Figs. 7, 8, and 9 are sections taken on the corresponding lines in Figs. 1, 3 and 5 85 respectively.

As shown in Figs. 1 to 6, A indicates the 90 longitudinal or warp wires of the fabric and B the transverse or lay wires. In Figs. 7 to 9, the foremost warp wire A¹ passes over the transverse wire B¹ thence beneath two transverse wires B² and B³, over the 95 wire B⁴, and thence beneath the next two transverse wires of which one only is shown at B⁵. The next warp wire indicated at A² passes beneath the two lay wires B¹ and B², thence over the lay wire B³, thence beneath the two lay wires B⁴ and B⁵, etc. The 100 third warp wire A³ shown particularly in Fig. 1 passes beneath the lay wire B¹, over the lay wire B², thence beneath the two lay wires B³ and B⁴, over the lay wire B⁵, etc. 105 The transverse wires B¹ to B⁵ are illus-

UNITED STATES PATENT OFFICE.

HAMILTON LINDSAY, OF CLEVELAND, OHIO, ASSIGNEE TO THE LINDSAY WIRE WEAVING COMPANY, OF CLEVELAND, OHIO, A CORPORATION OF OHIO.

SEAM FOR WOVEN-WIRE BELTS.

Application filed February 12, 1923. Serial No. 618,751.

To all whom it may concern:

Be it known that I, HAMILTON LINDSAY, a citizen of the United States, residing at Cleveland, in the county of Cuyahoga and State of Ohio, have invented a certain new and useful Improvement in a Seam for Woven-Wire Belts, of which the following is a full, clear, and exact description, reference being had to the accompanying drawings.

This invention relates to a seam for joining the ends of an endless wire belt which is useful in Fourdrinier paper machines. My invention is moreover especially concerned with a seam for lacing the ends of a belt having a special weave as set forth in my copending application Serial No. 525,403, filed December 28, 1921.

Briefly, the belt illustrated in my co-pending application embodies a fabric wherein the lower knuckles of the longitudinally extending or warp wires pass continuously beneath two or more transverse or lay wires, instead of only one. Accordingly, the warp wires are divided into groups, each preferably of three wires in number, during the weaving operation, and are so manipulated that one group forms one plane of the shed while the other two groups form the other plane of the shed, during the passage of the shuttle therebetween and across the loom. These groups are interchanged after each stroke of the shuttle whereby the fabric so formed has short knuckles on the upper side of the belt and long knuckles on the lower side thereof. This results in a construction which gives a longer wearing surface to the under side of the belt, thus increasing the life thereof.

One of the difficulties encountered in joining the ends of the belt above described is the provision of a seam which does not fill the interstices (which would render it difficult for water to pass through this seam when the belt is in use) and at the same time forms a sufficient support between the ends of the fabric so as not to strain the pulp. Another difficulty is the arrangement of closing wires which do not displace the lay wires so as to distort the mesh.

One of the causes for the difficulties above set forth is the fact that the lay wire on each end of the belt has usually heretofore been soldered to the ends of the warp wires. Usually some of the metal fills the inter-

stices thus preventing the normal passage of water through the mesh and accordingly affecting the quality of paper formed at that particular point. One of the reasons advanced for the necessity of soldering the end lay wire to the warp wires has been the distance between the short knuckles on such lay wire, which distance is considerably greater than that occurring in the standard weave.

Accordingly, one of the objects of my invention is the provision of a seam having sufficient space for the passage of water therethrough, and sufficient support between the ends of the fabric so that the pulp is properly drained and at the same time is supported adjacent the seam, whereby the paper is not weakened. Another object is the provision of a seam for use in a belt constructed in the manner above set forth which will not weaken the wires adjacent the ends of the fabric, and which may have sufficient strength to hold the ends of the belt in proper position without requiring the lay wires adjacent the end of the belt so to be soldered to the ends of the warp wires.

The preferred embodiment for carrying out my invention is illustrated in connection with the accompanying drawings, and is hereinafter described in detail. The essential features are summarized in the claims.

In the drawings, Figure 1 is a view showing a portion of the top of a belt having a weave constructed as heretofore described and illustrating the application of the seam forming wires; Fig. 2 is a view similar to Fig. 1 but showing the bottom side of the belt; and Fig. 3 is a section taken on the line 3-3 in Fig. 1.

As shown in the drawings, the longitudinal or warp wires of the fabric are indicated at A¹, A², A³, etc., while the transverse or lay wires on one end of the belt are indicated at B¹, B², B³, etc. and at the other end of the belt at BB¹, BB², etc. Thus the warp wire A¹ passes over the transverse wire B¹, thence beneath the next two transverse wires B² and B³ and over the wire B⁴, thence beneath the next two transverse wires B⁵ and B⁶, etc. The next warp wire indicated at A² passes beneath the two transverse wires B¹ and B², thence over the wire B³, thence beneath the next two transverse wires B⁴ and B⁵. The third warp wire A³, shown particularly in Fig. 1, passes beneath the lay

stitching wires forming outer loops over the same lay wire and inner loops over different lay wires, all of the inner loops of one stitching wire being over the same lay wire, and each lay wire having a short warp knuckle on one side of the stitching wire, and a closing wire passing alternately through said outer loops for joining the ends of the belt.

11. A seam for an endless belt wherein the weave comprises warp wires and lay wires, the warp wires having long knuckles on one side of the belt and short knuckles on the other side thereof, having two stitching wires passing over one end of the belt so as to provide outer and inner loops, each inner loop being positioned on every third row and adjacent a short warp knuckle, and a closing wire passing across the ends of the

belt and passing through the outer loops in one of the stitching wires.

12. A seam for an endless belt wherein the weave comprises warp wires and lay wires, the warp wires having long knuckles on one side of the belt and short knuckles on the other side thereof, having two stitching wires adjacent each end of the belt, each stitching wire forming outer loops over the end of the belt and inner loops over an inner lay wire and adjacent a short warp knuckle, and a closing wire passing alternately through the outer loops on each end of the belt.

In testimony whereof, I hereunto affix my signature.

HAMILTON LINDSAY.

seam may be accomplished without soldering or fusing the end lay wires with the severed ends of the warp wires.

I claim:—

- 5 1. A seam for an endless belt wherein the weave comprises warp wires and lay wires, the warp wires having long knuckles on one side of the belt and short knuckles on the other side thereof, having two stitching wires passing through the ends of the belt to form inner and outer loops, at least one of said stitching wires passing through the belt adjacent a short warp knuckle, the inner loops for said stitching wires being separated by at least one lay wire, and a closing wire connecting said outer loops. 70
- 10 2. A seam for an endless belt wherein the weave comprises warp wires and lay wires, the warp wires having long knuckles on one side of the belt and short knuckles on the other side thereof, having two stitching wires passing through the ends of the belt to form inner and outer loops, one of said stitching wires passing through the belt adjacent a short warp knuckle, the outer loops passing over the same lay wire, and the inner loops passing over different lay wires at least one of the inner loops on one stitching wire being separated by at least one lay wire from an inner loop on the other stitching wire, and a closing wire passing through the outer loops adjacent the ends of the belt. 75
- 15 3. A seam for an endless belt wherein the weave comprises warp wires and lay wires, the warp wires having long knuckles on one side of the belt and short knuckles on the other side thereof, having two stitching wires on one end of the belt, each of said wires passing through the belt adjacent a short warp knuckle to form inner loops, at least one inner loop of one stitching wire being separated from at least one inner loop of the other stitching wire by a lay wire, and a closing wire associated with at least one of said stitching wires for adjoining the ends of the belt. 80
- 20 4. A seam for an endless belt wherein the weave comprises warp wires and lay wires, the warp wires having long knuckles on one side of the belt and short knuckles on the other side thereof, having two stitching wires adjacent one end of the belt, at least one of the stitching wires passing through the belt adjacent a short warp knuckle, the stitching wires forming outer loops over the same lay wire and forming inner loops over different lay wires, said inner loops being separated by at least one transverse row, and a closing wire passing alternately through the outer loops for joining the ends of the belt. 85
- 25 5. A seam for an endless belt wherein the weave comprises warp wires and lay wires, the warp wires having long knuckles on one side of the belt and short knuckles on the other side thereof, having two stitching wires passing over the inner and outer ends of one stitching wire occupying the same longitudinal row as the outer loops of the other stitching wire, one of said stitching wires passing over a lay wire which has a short warp knuckle adjacent said loop, and a closing wire passing through the outer loops for joining the ends of the belt. 90
- 30 6. A seam for an endless belt wherein the weave comprises warp wires and lay wires, the warp wires having long knuckles on one side of the belt and short knuckles on the other side thereof, having two stitching wires on the ends of the belt to form inner and outer loops, at least one of said stitching wires passing over a lay wire which has a short warp knuckle adjacent said inner loop, the inner loops of each stitching wire passing through the same longitudinal row as the outer loops of the other stitching wire, and a closing wire passing through the outer loops for joining the ends of the belt. 95
- 35 7. A seam for an endless belt wherein the weave comprises warp wires and lay wires, the warp wires having long knuckles on one side of the belt and short knuckles on the other side thereof, having two stitching wires passing through one end of the belt to form inner and outer loops, and at least one of said stitching wires passing over a lay wire and between portions of short warp knuckles, the inner loops of one stitching wire occupying the same longitudinal row as the outer loops of the other stitching wire, and at least one of the loops of one wire being separated by a transverse row from at least one inner loop of the other wire, and a closing wire passing through the outer loops for joining the ends of the belt. 100
- 40 8. A seam for an endless belt wherein the weave comprises warp wires and lay wires, the warp wires having long knuckles on one side of the belt and short knuckles on the other side thereof, having two stitching wires passing through one end of the belt to form inner and outer loops, at least one stitching wire passing through the belt adjacent a short warp knuckle, all of the inner loops of one stitching wire passing over the same lay wire and at least one inner loop of the other stitching wire being separated from all of the inner loops of the other stitching wire by at least one transverse row, and a closing wire passing through the outer loops of at least one stitching wire for joining the ends of the belt. 105
- 45 9. A seam for an endless belt wherein the weave comprises warp wires and lay wires, the warp wires having long knuckles on one side of the belt and short knuckles on the other side thereof, having two stitching wires passing over the inner and outer ends of one stitching wire occupying the same longitudinal row as the outer loops of the other stitching wire, one of said stitching wires passing over a lay wire which has a short warp knuckle adjacent said loop, and a closing wire passing through the outer loops for joining the ends of the belt. 110
- 50 10. A seam for an endless belt wherein the weave comprises warp wires and lay wires, the warp wires having long knuckles on one side of the belt and short knuckles on the other side thereof, having two stitching wires adjacent one end of the belt, at least one of the stitching wires passing through the belt adjacent a short warp knuckle, the stitching wires forming outer loops over the same lay wire and forming inner loops over different lay wires, said inner loops being separated by at least one transverse row, and a closing wire passing alternately through the outer loops for joining the ends of the belt. 115
- 55 11. A seam for an endless belt wherein the weave comprises warp wires and lay wires, the warp wires having long knuckles on one side of the belt and short knuckles on the other side thereof, having two stitching wires passing over the inner and outer ends of one stitching wire occupying the same longitudinal row as the outer loops of the other stitching wire, one of said stitching wires passing over a lay wire which has a short warp knuckle adjacent said loop, and a closing wire passing through the outer loops for joining the ends of the belt. 120
- 60 12. A seam for an endless belt wherein the weave comprises warp wires and lay wires, the warp wires having long knuckles on one side of the belt and short knuckles on the other side thereof, having two stitching wires passing over the inner and outer ends of one stitching wire occupying the same longitudinal row as the outer loops of the other stitching wire, one of said stitching wires passing over a lay wire which has a short warp knuckle adjacent said loop, and a closing wire passing through the outer loops for joining the ends of the belt. 125
- 65 13. A seam for an endless belt wherein the weave comprises warp wires and lay wires, the warp wires having long knuckles on one side of the belt and short knuckles on the other side thereof, having two stitching wires passing over the inner and outer ends of one stitching wire occupying the same longitudinal row as the outer loops of the other stitching wire, one of said stitching wires passing over a lay wire which has a short warp knuckle adjacent said loop, and a closing wire passing through the outer loops for joining the ends of the belt. 130

of the belt to form inner and outer loops, at least one of the stitching wires passing over the end of the belt adjacent a short warp knuckle, all of the inner loops of one stitching wire passing over the third lay wire remote from the end of the belt, and all of the inner loops of the other stitching wire passing over the fifth lay wire remote from the end of the belt, and a closing wire passing through the outer loops for joining the ends of the belt.

10. A seam for an endless belt wherein the weave comprises warp wires and lay wires, the warp wires having long knuckles on one side of the belt and short knuckles on the other side thereof, having two stitching wires passing over the ends of the belt to form inner and outer loops, one of said stitching wires passing through the belt adjacent a short warp knuckle, all of said inner loops on each wire passing over odd numbered lay wires remote from the end of the belt, and a closing wire passing through the outer loops for joining the ends of the belt.

11. A seam for an endless belt wherein the weave comprises warp wires and lay wires, the warp wires having long knuckles on one side of the belt and short knuckles on the other side thereof, having two stitching wires passing over the ends of the belt to form inner and outer loops, one of said stitching wires passing through the belt ad-

jacent a short warp knuckle, all of said inner loops on each wire passing over odd numbered lay wires remote from the end of the belt, and the inner loop of each wire passing through the same longitudinal row as the outer loop of the other wire, and a closing wire passing through the outer loops for joining the ends of the belt.

12. A seam for an endless belt wherein the weave comprises warp wires and lay wires, the warp wires having long knuckles on one side of the belt and short knuckles on the other side thereof, having two stitching wires passing through the ends of the belt to form inner and outer loops, at least one of the stitching wires passing through the belt adjacent a short warp knuckle, the outer loops passing over an end lay wire, the inner loops of one stitching wire passing over one lay wire remote from the end of the belt, and the inner loops of the other stitching wire also passing over another lay wire remote from the end of the belt, there being at least one transverse row between the inner loops of said wires, and at least one transverse row between the inner loops of one wire and the outer loops of both wires, and a closing wire passing through the outer loops to join the ends of the belt.

In testimony whereof I hereunto affix my signature.

HAMILTON LINDSAY.
